UNITED STATES PATENT OFFICE.

PAUL W. RUNYAN, OF SPRINGFIELD, OHIO, ASSIGNOR TO THE NATIONAL BROODER COMPANY, OF SPRINGFIELD, OHIO, A CORPORATION OF OHIO.

DESIGN FOR A BROODER STOVE.

Application filed August 4, 1924. Serial No. 10,372. Term of patent 14 years.

To all whom it may concern:

Be it known that I, PAUL W. RUNYAN, a citizen of the United States, residing at Springfield, in the county of Clark and State of Ohio, have invented a new, original, and ornamental Design for Brooder Stoves, of which the following is a specification, reference being had to the accompanying drawing, forming part thereof.

Fig. 1 is a view in perspective of the front of the stove.

Fig. 2 is a view in perspective of a side of the stove.

I claim:

The ornamental design for a brooder stove, as shown.

PAUL W. RUNYAN.
